DISPLAY RACK FOR CROCKERY OR SIMILAR ARTICLE

Morris T. Grode, Jackson Heights, N. Y.

Application October 10, 1951, Serial No. 16,895

Term of patent 7 years

(Cl. D80—9)

To all whom it may concern:

Be it known that I, Morris T. Grode, a citizen of the United States, residing at 35—46 81st Street, Jackson Heights, Long Island, New York, have invented a new, original, and ornamental Design for a Display Rack for Crockery or Similar Article, of which the following is a specification, reference being had to the accompanying drawing, forming part thereof.

Fig. 1 is a perspective view of a display rack for crockery or similar article, showing my new design;

Fig. 2 is a side elevational view; and

Fig. 3 is a fragmentary plan view thereof.

I claim:

The ornamental design for a display rack for crockery or similar article, as shown.

MORRIS T. GRODE.
